UNITED STATES PATENT OFFICE.

LOUIS A. CASGRAIN, OF BEVERLY, MASSACHUSETTS.

STARTING DEVICE FOR INTERNAL-COMBUSTION MOTORS.

1,171,170.

Specification of Letters Patent.

Patented Feb. 8, 1916.

Application filed December 8, 1913. Serial No. 805,298.

To all whom it may concern:

Be it known that I, LOUIS A. CASGRAIN, a citizen of the United States, residing at Beverly, in the county of Essex and State of Massachusetts, have invented certain new and useful Improvements in Starting Devices for Internal-Combustion Motors; and I do hereby declare the following to be a full, clear, and exact description of the invention, such as will enable others skilled in the art to which it appertains to make and use the same.

The present invention relates to starting devices for internal combustion motors and more particularly to devices of this character which are employed for starting automobile motors.

It is highly desirable that some means be provided for starting the motor of an automobile from the seat, thus enabling the operator to start the motor any time without the necessity of cranking the motor from the front of the car. It is furthermore desirable that the mechanism for starting the motor shall be arranged to rotate the crank shaft with a minimum degree of manual effort upon the part of the operator.

One object of the present invention is to provide a starting device of an improved form which is simple and compact in its construction and which may be readily manipulated with a comparatively slight effort to rotate the crank shaft of the motor.

A further object of the invention is to so construct and arrange the starting device that it may be applied to existing automobile chassis without the necessity of making any substantial changes in the chassis.

With these objects in view the various features of the invention consist in certain novel features of construction, combinations and arrangements of parts hereinafter described and claimed, the advantages of which will be obvious to those skilled in the art from the following description.

In the accompanying drawings illustrating the preferred form of the invention; Figure 1 is a perspective view representing the front portion of an automobile chassis with the improved starting device applied thereto; Fig. 2 is a detail illustrating a side elevation of the starting mechanism applied to the motor crank shaft; Fig. 3 is a detail showing a longitudinal section of the starting handle and illustrating the method of supporting the handle where it passes

through the dash; Fig. 4 is a detail showing a section of the bearing for the starting handle taken in a plane at right angles to Fig. 3; and Fig. 5 is a detail illustrating a section upon the line 5—5 of Fig. 2, showing the construction of the ratchet and pawl clutch for rotating the crank shaft.

In the illustrated embodiment of the invention the starting device is applied to an automobile chassis of a well-known type having a frame 1 in which a motor 2 is supported and a dash 3 through which the steering column 4 passes. As a large proportion of these starting devices are applied to automobiles after they have been built it is desirable to construct them in such a manner that they may be applied to the chassis with a minimum change and that, furthermore, the starting mechanism shall be simple and compact in construction in order to occupy the relatively small vacant space between the motor and the hood of the machine. The efficiency and consequent value of the starting device depends in part upon its adaptability to the existing chassis and also upon the ease with which it may be operated to rotate the crank shaft. In the present construction the starting device is provided with a handle conveniently accessible to the operator from the seat, a one direction clutch connected to the crank shaft of the motor, an operating arm loosely supported upon the crank shaft and connected with the clutch, and a flexible connection fixedly secured at one end and connected at its opposite end to the starting handle and engaging with the end of the operating arm to cause a movement of the operating arm in accordance with the movement of the starting handle. To this end a starting handle 10 projects from the dash into a position conveniently accessible to the operator from the seat and is connected with a rod 12 slidingly supported in a bearing 13 secured to the dash, as shown clearly in Fig. 3. The rod 12 is connected at its lower end to a flexible connection 14 which is fixedly secured to a bracket 15 at its opposite end and passes over a pulley 17 journaled in the end of an arm 18. The bracket 15 is secured to the frame 1 of the chassis and is provided with an idler roll 20 around which the connection 14 passes. The operating arm 18 is loosely journaled upon a bearing 21 secured to the crank shaft 22 of the motor by a pin 23. As shown clearly in Fig. 5 of the draw-

- ings, the arm 18 is journaled upon ball bearings 24 which are adjusted and maintained in position by collars 25 and 26. It may be explained at this time that it is usual in this type of chassis to secure a fan pulley to the end of the crank shaft 22 and that the bearing 21 is applied to the crank shaft by removing the fan pulley and substituting for it the bearing shown, which is 10 provided with a similar fan pulley 27. In the illustrated embodiment of the invention the arm 18 consists of two side members 28 secured together and carrying between them the idler pulley 17 and a pawl 30 fulcrumed 15 at 33. The bearing member 21 is provided with two sets of teeth indicated respectively at 31 and 32 with which the pawl engages upon a movement of the arm in the direction of the arrow to rotate the crank shaft. 20 The pawl is normally retained in engagement with the ratchet by a spring 34 fulcrumed upon the arm at 35 and bearing at one end against the under side of the pawl and at its opposite end against the bearing, 25 as shown in Fig. 2 of the drawings.

With this construction, when the operator exerts a pull upon the starting handle 10 the flexible connection 14 will be operated to rock the arm in the direction of the 30 arrow and partially rotate the crank shaft. It will be further observed that owing to the fact that one end of the flexible connection is fixedly secured, the pull upon the end of the arm 18 tending to turn it will be 35 double the pull exerted on the starting handle, thus causing the turning effort applied to the crank shaft to be twice the pull exerted upon the starting handle, multiplied by the length of the arm 18 when this arm 40 reaches a position normal to the flexible connection. It will be noted that as the arm 18 rises the torque applied to the crank shaft increases, reaching its maximum when the arm is vertical and the piston is at approximately the limit of its compressing movement. This construction provides an extremely simple and efficient method of turning the crank shaft with the application of a minimum amount of effort to 45 the starting handle. Under ordinary conditions a quarter to a third of a rotation of the crank shaft is sufficient to start the motor as this moves the piston which is on the compression stroke past the point at 50 which the charge is fired. The movement of the arm in opposite directions is limited by the casing 37 supported beneath the crank shaft and arranged to engage with the under face of the arm when in an inoperative position, and with a shoulder 38 formed upon the arm when positioned substantially as shown in dotted lines in Fig. 2. 55 It frequently happens that when the crank shaft is rotated the motor back-fires, as it is termed, causing a reverse rotation of the 60 crank shaft. It will be obvious that this reverse rotation will cause a like movement of the starting device and if no means were provided for disengaging the starting device from the crank shaft or for cushioning the backward movement, an unpleasant shock would be communicated to the hand of the operator and the starting device itself might be seriously injured. In the present construction mechanism is provided 70 for automatically retarding the time at which the firing takes place to prevent this back-firing of the motor, and in addition, mechanism is provided for automatically disengaging the operating arm from the crank shaft if a reverse rotation of the 75 crank shaft takes place. To this end the arm 18 is provided with a depending curved finger 40 which is arranged to engage and rock an arm 41 projecting from the usual 80 timer 42, thus causing the spark to be automatically retarded whenever the arm is actuated to rotate the crank shaft. The outer free end of the pawl 30 carries a dog 43 which is normally positioned, as shown 85 in Fig. 2, with its upper end bearing against the flexible connection 14 to retain the pawl out of engagement with the co-operating ratchet. In the illustrated embodiment of the invention the flexible connection consists of a link chain which rocks the dog into the dotted line position shown in Fig. 2 when the chain is moved forward to rock the arm, thus allowing the pawl 30 to engage with its co-operating ratchet. If 90 the crank shaft is rotated in a reverse direction, however, to rock the arm back to its initial position the lower portion of the chain will be moved at twice the speed of the end of the arm, thus causing a relative 95 movement of the chain and arm which returns the dog to the position shown in full lines in Fig. 2 and disengages the pawl from the ratchet. The dog 43, as shown clearly 100 in Fig. 2, is provided with a tail upon its lower end which engages with the end of the pawl to maintain the dog in an upright position and keep the pawl out of engagement with the ratchet. This disengaging 105 of the pawl by the dog 43 also takes place 110 when the starting handle is released to allow the arm to be returned by a tension spring 47 connecting the arm with a portion of the frame. In order to normally 115 aid in the return of the dog to its initial 120 position a leaf spring 48 is secured in the arm and is arranged to bear against the under side of the dog when in its inoperative 125 position. A four cylinder motor normally stops in what is known as a balanced position with all of the pistons at approximately the same height, locating one of the teeth 31 in position to be engaged by the operating pawl. If the motor is approximately 130 balanced the tooth 31 will be so po-

sitioned that the rocking of the pawl will move the piston which is on the compression stroke past the firing point. It sometimes happens, however, that the motor stops with the piston on the compression stroke lower than normal, positioning the working tooth 31 where it cannot be engaged by the operating pawl. In order to bring the motor back to a balanced position, locating teeth 10 are provided which may be engaged by the pawl to partially rotate the crank shaft and bring it into a position in which the pawl is enabled to engage with the working teeth 31 in the usual manner. To this end a pair 15 of locating teeth 32 are arranged in advance of the working teeth at an angle of less than ninety degrees. With this construction, if the pawl cannot engage with the working tooth which is uppermost it is 20 then advanced to engage with the corresponding locating tooth which enables the crank shaft to be turned into a position where the pistons balance and brings the working tooth into a position where it may 25 be engaged by the operating pawl.

It will be obvious from the preceding description that the dog 43 will normally serve to disengage the pawl from the ratchet, either when the starting handle is released 30 or when the crank shaft is rotated reversely to its normal direction of rotation. In order to insure the positive removal of the pawl from the driving ratchet, however, if the dog 43 should fail to operate it will 35 be noted that the chain 14 is provided with an enlarged link 50 which engages with the upper face of the pawl 30 and positively removes the pawl from engagement with the ratchet whenever the chain is retracted. 40 Normally the dog 43 disengages the pawl prior to the movement of the link 50 into an operative position and it is only when the dog fails to operate and the arm 18 has been returned to approximately the position 45 shown in full lines in Fig. 2 that the link contacts with the pawl and disengages it from the coöperating ratchet. In order to prevent injury to the spring 34 caused by an undue movement of the pawl about its 50 fulcrum in the arm when the arm and bearing member are removed from the motor a stop member 51 is secured to the under side of the pawl and is provided with a face bearing against the pin 35 to limit the 55 movement of the pawl in this direction.

The starting rod 12 is rectangular in cross section to maintain a fixed operative relation between the rod and chain 14, and the passage in the bearing member, as shown 60 clearly in Figs. 3 and 4, is also rectangular in cross section and is tapered in two planes, thus allowing a limited angular movement of the starting rod without cramping it in the bearing 13. The recoil of the starting 65 handle, either when released, or when the

motor back-fires, is cushioned by a coiled spring 53 which is inclosed within a casing 54 and interposed between a collar 55 secured to the upper end of the rod 12 and the lower end of the casing 54. The casing 54 is secured at its upper end to the starting handle 10 and loosely surrounds the rod 12, and with this construction the spring 53 will yield when the starting handle is released or when the motor back-fires 70 and the casing 54 engages with the bearing. The spring is light enough to ordinarily yield when the piston passes over the highest point of compression and when the downward stroke of the piston commences the 75 spring tends to expand, imparting an accelerated movement to the piston with the application of a continued uniform pull to the starting handle. In order to further cushion the return movement of the starting 80 handle a yielding washer or buffer 56 is interposed between the lower end of the casing 54 and the bearing 13. With this construction it will be noted that the operator is enabled to grasp the starting handle 85 and turn it into any position which is most convenient, and the starting handle may be then moved in a linear direction to rotate the crank shaft, which direction may be varied slightly by swiveling the rod 12 in 90 the bearing if the direction of pull does not coincide exactly with the longitudinal axis of the rod 12.

While it is preferred to employ the specific construction and arrangement of parts 100 shown and described, it will be understood that this construction and arrangement is not essential except so far as specified in the claims and may be changed or modified without departing from the broader features 105 of the invention.

Having thus described the invention, what is claimed is:

1. A starting device for internal combustion motors, having in combination, a starting handle, a one direction clutch adapted to be connected with the crank shaft of the motor, an operating arm supported upon the crank shaft and connected with the clutch, and a flexible connection passing over 110 the end of the operating arm and fixedly secured at one end and connected to the starting handle at its opposite end and arranged to apply double the pull upon the end of the arm that is exerted upon the starting handle. 115

2. A starting device for internal combustion motors, having, in combination, a starting handle, a one-direction clutch adapted to be connected to the crank shaft of the motor, an operating arm supported upon the 120 crank shaft and connected with the clutch, and a flexible connection fixed at one end and arranged to apply substantially double the pull upon the end of the arm that is exerted upon the starting handle, and passing 125

over the end of the operating arm and arranged to rock the arm in a direction to impart an increasing torque to the crank shaft.

3. A starting device for internal combustion motors, comprising a starting handle, a rod connected with the handle, connections between the rod and crank shaft, including a one direction clutch, and a bearing located in the dash provided with a tapered bore in which the rod is slidably supported to permit an angular movement of the rod with relation to the bearing when the starting handle is actuated by the operator.

4. A starting device for internal combustion motors, having in combination, a starting handle, a ratchet secured to the crank shaft of the motor, an operating arm, a pawl carried by the arm and normally retained in engagement with the ratchet, a chain connected with the free end of the arm, and a dog supported by the pawl and arranged to be actuated by the chain and disengage the pawl from the ratchet upon a reverse movement of the chain.

5. A starting device for internal combustion motors, comprising a starting handle, an operating arm, a one direction clutch adapted to connect the arm with the motor crank shaft, a bracket, an idler roll carried in the bracket, and a flexible connection operatively engaging with the end of the arm and connected at its opposite ends to the bracket and the starting handle.

6. A starting device for internal combustion motors, having in combination, a starting handle, an operating pawl, connections between the starting handle and pawl, a ratchet secured to the crank shaft and having working teeth normally arranged to be engaged by the pawl to rotate the crank

shaft and locating teeth positioned less than ninety degrees in advance of the working teeth to rotate the crank shaft into a position where one of the working teeth may be engaged by the pawl to move the piston 45 upon the compression stroke past the firing point.

7. A starting device for internal combustion motors, having in combination, a starting handle, an operating arm, a one direction clutch normally connecting the arm and crank shaft of the motor, a flexible member connected with the free end of the arm, and a dog arranged to be actuated by the flexible member immediately when retracted to disengage the clutch.

8. A starting device for internal combustion motors, comprising a one direction clutch, an operating arm connected to the clutch, a chain operatively connected with 60 the arm and provided with an enlarged link, and a dog supported upon the arm and arranged to be engaged by the enlarged link upon a reverse movement of the chain to disconnect the one direction clutch.

9. A starting device for internal combustion motors, having, in combination, a starting handle, an operating arm supported upon the motor crank shaft, a driving pawl fulcrumed upon the arm, a flexible member 70 connecting the starting handle and free end of the arm, and a dog supported upon the free end of the driving pawl and arranged to be actuated by the flexible member immediately when retracted to disconnect the 75 driving pawl from the crank shaft.

LOUIS A. CASGRAIN.
